(57) **CLAIM**

The ornamental design for an lung simulator, as shown and described.

DESCRIPTION

FIG. 1 is a perspective view of one embodiment of the lung simulator;

FIG. 2 is a front view of the lung simulator of FIG. 1;

FIG. 3 is a rear view of the lung simulator of FIG. 1;

FIG. 4 is a left side view of the lung simulator of FIG. 1;

FIG. 5 is a right side view of the lung simulator of FIG. 1;

FIG. 6 is a bottom view of the lung simulator of FIG. 1;

FIG. 7 is a top view of the lung simulator of FIG. 1; and,

FIG. 8 is a perspective view of an alternative embodiment of the lung simulator of FIG. 1 without a slide thereof.

The broken lines of the drawing are for illustrative purposes only and form no part of the claimed design. These broken lines show a replaceable bag (similar to a balloon) which can be connected via a nipple at the inside of the lung simulator. In FIG. 8 broken lines showing a bag are omitted to facilitate better understanding of the construction of the lung simulator.
